Primary Examiner — Cynthia Ramirez*Assistant Examiner* — Laura H Yu(74) Attorney, Agent, or Firm — Banner & Witcoff, Ltd.(57) CLAIM

The ornamental design for a shoe, as shown and described.

DESCRIPTION

FIG. 1 is a front perspective view of a shoe showing my new design;
FIG. 2 is a side view thereof;

FIG. 3 is an opposite side view thereof;

FIG. 4 is a rear view thereof; and,

FIG. 5 is a rear perspective view thereof.

The uneven-length broken lines immediately adjacent to the shaded area define the bounds of the claimed design and form no part thereof. The uneven-length broken lines depicting the remainder of the shoe show features that form no part of the claimed design. The five unshaded regions within the shaded area that are demarcated by uneven-length broken lines represents a feature that forms no part of the claimed design. The even-length broken lines within the shaded area represent a feature that forms no part of the claimed design.
